Patented Aug. 27, 1918.

UNITED STATES PATENT OFFICE.

LESTER E. OHMART, OF HOPE, KANSAS.

SILo ATTACHMENT.

1,276,801.

Specification of Letters Patent.

Patented Aug. 27, 1918.

Application filed March 9, 1918. Serial No. 221,432.

To all whom it may concern:

Be it known that I, LESTER E. OHMART, a citizen of the United States, residing at Hope, in the county of Dickinson and State 5 of Kansas, have invented certain new and useful Improvements in Silo Attachments, of which the following is a specification.

My invention relates to devices for facilitating the lifting into place of the blower 10 pipe, hood and other connections whereby the ensilage is conveyed from the cutter on the ground, over the top, and into the interior of the silo, and as well to the means for holding the upper end of the conveyer 15 and its attachments while in operation. The object is to produce a simple, cheaply made, strong, durable, light, portable and adjustable device to facilitate the lifting of the conveyer from the ground to the top; 20 also to provide in connection therewith a means for lifting the distributer pipe inside the silo; also to provide in connection therewith a suitable means for securely anchoring the upper end of the conveyer to the silo wall. 25 The invention comprises a frame which is made so as to be adjustable to any width of silo wall and formed with a pair of outwardly projecting spaced arms, together with a pulley removably supported between 30 the arms; it also comprises in connection therewith, a second pair of spaced arms with a pulley above the interior of the silo for lifting the distributer; it also comprises certain parts, improvements and combinations 35 relating thereto as hereinafter set forth and claimed.

In the drawings forming a part of and accompanying this specification, I have shown my invention in its preferred form 40 and what I deem to be the best mode of applying the principles thereof; but it is to be understood that, within the scope of the appended claims, I contemplate changes in form, proportions and materials, the trans- 45 position of parts, and the substitution of equivalent members, without departing from the spirit of my invention.

Figure 1 is a vertical sectional elevation on a plane indicated by the line 1—1 in Fig. 50 3. Fig. 2 is a front elevation, that is, a view from the outside of the silo. Fig. 3 is a plan. Fig. 4 is an elevation of one of the pulley-supporting arms, the view being indicated by the arrow 4 in Fig. 1. Fig. 5 is

a sectional elevation of the other arm, on a 55 plane indicated by the line 5 in Fig. 3, the pulley axle being removed.

Similar reference characters indicate similar parts throughout the several views.

I use two L-shaped bracket arms each 60 comprising a vertical leg 2 and a horizontal leg 3, and the vertical leg being bent to form a diagonal brace 4. The two bracket members are held in rigid spaced relation by means of braces 5 extending between the 65 vertical legs. Also I use two other L-shaped brackets each comprising a vertical leg 6 and a horizontal leg 7; and these are preferably made of angle-bars as indicated in order the better to withstand the strains 70 encountered. In each of the horizontal legs of the last-named brackets are two slots 8, 8, and through each slot extends a bolt 9, which also extends through a hole in the horizontal portion of the first-named 75 bracket, as shown in Figs. 1 and 5 most clearly. By means of the bolts, the legs are held in parallel relation respectively; and it is designed that the upper end of the silo 80 wall shall be clamped between the legs 2, 2 (on the outside) and the legs 6, 6 (on the inside). By loosening the bolts, the vertical legs may be spread farther apart from each other, so that, within the range permitted by the length of the slots 8, 8, the device 85 may be adjusted to fit any thickness of silo wall. The outer ends of the horizontal legs 7, 7, extend preferably beyond the outer ends of the legs 3, 3, and in one of them is a hole 10 and in the other a slot 11. The hole 90 is engaged by the eyelet 12 formed in the end of the axle 13 whose free end is adapted to fit into the slot 11, said axle being thus free to be swung across and supported horizontally on the arms or to be thrown back 95 out of the way so as to leave the space clear between the arms or to be lifted for the purpose of passing a rope over the spool-shaped pulley 14 carried thereon.

Secured to the vertical legs of the second-named L-shaped brackets are a pair of sleeves or sockets 15, 15 in which are set the lower ends of the rods 16, 16, respectively, said rods being extended out over the interior of the silo as shown and carrying 100 15 at their ends another spool-shaped pulley 17, and said rods being also spaced apart in the same manner as the horizontal out-

wardly projecting legs hereinbefore described. The pulley is mounted on a suitable axle 18 extending between the two rod ends. The rods may be adjusted vertically 5 in their sockets and are held securely in adjusted position by means of the set screws 19.

The device as described being secured to the top of the silo wall, a rope 20 is passed over the pulley 14 and one end secured to the conveyer 21 below its upper end. Then by any suitable power, the conveyer is lifted into place, its upper end passing either inside or outside the pulley, and its lower end being properly supported when the conveyer is fully extended. If the upper end comes up outside the pulley, it is an easy matter, when the lower end is supported, to throw back the pulley and bring the conveyer tube in between the arms, with the deflector 22 and the hopper joint 23 extending inwardly between the rods 16, 16; and, whenever desired, the pipe may be securely lashed to the parts by means of rope. The distributor pipe sections 25 may then be lifted into place to connect with the hopper joint 23 by means of the rope 24 passing over the pulley 17.

Where the thickness of the wall is known, 30 the adjustment of the device thereto may be made on the ground before the device is carried to the top, thereby avoiding the necessity of the somewhat dangerous expedient of doing the adjusting in a precarious position on top of the silo wall. The device being light, can be easily carried to the top by one man who can also slip it over the top of the wall and who can pass a cord over the pulley to draw up the 40 stronger rope by which the lifting of the conveyer is done. Also, the one man can guide the upper end of the conveyer into place and throw the pulley off or on, as may be required, and can attend to the lashing, etc. Heretofore, this has been done by means of blocks and tackle, which are cumbersome to handle, and no convenient means has been devised for attaching same to the top of the wall.

50 I use the uninclosed spool-shaped pulley in order to facilitate the handling of the rope at the various stages in erecting, holding, and taking down the conveyer and parts, and to prevent the swinging of the

conveyer, as by a high wind, from throwing 55 the rope off of the pulley.

Having thus described my invention, what I claim as new is—

1. The combination of a pair of L-shaped brackets each comprising a horizontal leg 60 and a vertical leg and the vertical leg being upturned to form a diagonal brace, cross-braces rigidly securing said brackets together in spaced relation, a second pair of similarly formed brackets formed with slots 65 in their horizontal legs, bolts extending through said slots and into the horizontal legs of the first-named brackets, the vertical legs being in spaced parallel relation and adapted to bear against the outer and 70 inner face of a wall, and axle hinged to the free end of one of the horizontal legs of the second-named pair of brackets and supported on the free end of the other bracket of said pair and a spool-shaped pulley 75 mounted on said axle.

2. The combination of a pair of parallel spaced L-shaped brackets rigidly secured together, another pair of parallel spaced brackets, the corresponding legs of corresponding brackets being parallel with each other and the vertical legs of the one pair being spaced apart from the other pair so as to be adapted to embrace opposite sides of a wall, bolt-and-slot connections for adjustably securing the horizontal legs together, and a pulley and axle hinged to the outer end of one of said horizontal legs and laid across the space between said spaced legs and supported on the opposite leg. 90

3. The combination of a frame formed with outwardly projecting spaced pulley-supporting arms and formed to fit against the outer face of a wall, a pair of brackets formed to fit against the inner face of the 95 wall and adjustably secured to said frame and formed with vertical sockets, a pulley removably supported on the outer ends of said arms and spanning the space therebetween, a pair of inwardly extending arms 100 having vertical stems slidably fitting in the respective sockets, set-screws for holding said stems in said sockets, and a pulley spanning the inner ends of said last-named arms. 105

In testimony whereof I have hereunto affixed my signature.

LESTER E. OHMART.
